DESIGN FOR A BLOUSE

Hilda Newman, New York, N. Y., assignor to
The Winston Sportswear Corporation, New York, N. Y.

Application November 25, 1946, Serial No. 135,044

Term of patent 3½ years

(Cl. D3—25)

To all whom it may concern:

Be it known that I, Hilda Newman, a citizen of Czechoslovakia, residing at New York, New York, have invented a new, original, and ornamental Design for a Blouse, of which the following is a specification, reference being had to the accompanying drawing, forming a part thereof.

Figure 1 is a front view of a blouse showing my new design.

Fig. 2 is a rear view thereof, on a reduced scale.

I claim:

The ornamental design for a blouse, as shown.

HILDA NEWMAN.
